UNITED STATES PATENT OFFICE.

ESTON G. BROOKSHIRE AND HERBERT G. WILES, OF KANSAS CITY, KANSAS.

STOP-MOTION FOR SPINNING-FRAMES.

1,108,127.

Specification of Letters Patent. Patented Aug. 25, 1914.

Application filed August 30, 1913. Serial No. 787,543.

To all whom it may concern:

Be it known that we, ESTON G. BROOKSHIRE and HERBERT G. WILES, citizens of the United States, residing at Kansas City, in 5 the county of Wyandotte and State of Kansas, have invented a new and useful Stop-Motion for Spinning-Frames, of which the following is a specification.

This invention has reference to improvements in stop motions for spinning frames, and its object is to provide an automatic stop motion which will act when the bobbins run over, and thereby save loss of time and material.

15 In accordance with the present invention there is provided a mechanism which is automatically set by the starting of the frame and in the event of any of the bobbins running over the stop motion is released and automatically moves in a direction to shift the belt from the tight to the loose pulley when the motion is employed on a machine so driven, but in the event of other types of drive the same operation takes place.

25 Considering the driving power as being applied through a belt there is provided a latch lever movable by the shift rod of the belt shifter in a direction to compress a spring and at the same time latch the lever in the new position. Connected to the traverse rod of the frame is a member movable with the traverse rod in a direction to engage a portion of the latch structure in a manner to release the latched lever to the 35 action of the spring, whereupon the belt is shifted to the loose or idle pulley and the frame stops. The operation is entirely automatic and hence requires no attention from the operator.

40 The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such 45 changes and modifications mark no material departure from the salient features of the invention.

In the drawings:—Figure 1 is an elevation with some parts in section of the improved stop motion and also showing a small portion of a spinning frame, the stop mo-

tion being shown in the released position. Fig. 2 is a plan view of the structure of Fig. 1, also showing some parts in section and omitting portions of the spinning frame shown in Fig. 1. Fig. 3 is an end elevation of parts of the spinning frame showing the invention attached. Fig. 4 is a front elevation with some parts in section of the stop motion illustrated in Fig. 1, together with adjacent portions of the spinning frame and showing the parts in the latched position.

Referring to the drawings there is shown a portion of a spinning frame 1 which may be of ordinary construction, and, therefore, requires no detailed description, wherefore reference will be made to only such parts as coact directly with the structure of the present invention, such parts including a belt shifter 2, a drive belt 3, tight and loose 55 pulleys 4 and 5, respectively, a shifter rod 6 and a traverse rod 7, as well as one end frame 8 of the machine.

There is provided a bracket 9 which in the particular construction illustrated is of 60 substantially U-shape with bifurcated legs 10, 11, respectively.

The bracket is made fast to a cross member 12 of the frame 8 by a bolt 13 having one end extended in the form of a plain rod 14 and located about midway of and substantially parallel to the legs 10 and 11.

The bifurcated leg 10 is formed with passages for a pivot pin 15 traversing it, and mounted on this pivot pin is a lever 16 having a long leg 17 and a short leg 18. The long leg terminates in a short finger 19 behind which engages a bent end 20 of a rod 21 made fast by a collar 22 or otherwise to the shifter rod 6, the collar 22 permitting 75 adjustment of the rod 21 lengthwise of the rod 6 as may be needed.

The short leg 18 of the lever 16 has a passage 23 therethrough in position to be traversed by the rod 14, and between the short 80 leg 18 and the bracket 9 the rod 14 is surrounded by a spring 24 tending at all times to hold the long leg 17 of the lever 16 in engagement with the end 20 of the rod 21, and the arrangement is such that the spring 105 24 is always under considerable compression even when in its relatively extended position, as shown in Fig. 1, and in this position the lever 16 is so located that the belt 3 is on the loose pulley 5. When the shifter 110 rod 6 is moved in a direction to cause the belt 3 to leave the pulley 5 and move on to

the pulley 4, the rod 21 engaging the arm 17 of the lever 16 causes the latter to rock in a direction to move the arm 18 toward the yoke of the bracket 9, thereby correspondingly compressing the spring 24.

Mounted in the bifurcated arm 11 of the yoke 9 is an angle latch lever 25 having one arm 26 provided with an elongated wear plate 27 which adjacent to the angle of the lever 25 terminates in a shoulder 28. The lever 25 has another angle arm 29 which may be heavy enough to overbalance the arm 27, but this overbalancing may be augmented by the presence of a weight 30, the arm 29 having an extension 31 from which the weight 30 is hung and this extension 31 is on the side of the pivot pin 32 of the lever 25 remote from the arm 26.

The shorter arm 18 of the lever 16 is provided with a wear plate 33 in position to move over the wear plate 27 and ultimately drop behind the shoulder 28, the lever 25 yielding to such movement of the lever 16, while the weight 30 or the preponderating arm 29 if heavy enough causing the lever 25, which is in the nature of a latching lever, to then move into the path of the shorter arm 18 of the lever 16, wherefore the latter is held in the latched position against the normal tendency of the spring 24.

Mounted on the traverse rod 7 is a collar 34 which may be held thereto by set screws 35, so that the collar can be readily adjusted lengthwise of the rod. This collar has a finger 36 projecting from one side, and carried by this finger is a rod 37 having a free end 38 so located as to engage the arm 29 of the lever 25 near its free end and where the arm 29 is engaged by the rod extension 38 it may have a face 39 so related to the rod 38 and to the pivot pin 32 that the requisite rocking of the lever 25 may take place without liability of escape of the rod 38 therefrom.

Let it be assumed that the parts are in the position shown in Fig. 1, in which case the end 33 of the lever 16 is in engagement with the face of the plate 27 and the spring 24 is extended, while the belt 3 is on the pulley 5 and the end 20 of the rod 21 is in engagement with the end 19 of the arm 17. Now, when the spinning frame is started, the shifter rod 6 is moved toward the left as viewed in Fig. 1, thus carrying the belt 3 from the pulley 5 to the pulley 4, and at the same time rocking the lever 16 on its pivot 15 in a direction to compress the spring 24 and carry the end 33 of the arm 18 behind the shoulder 28, the lever 25 yielding for the purpose and then returning under the action of the weight 30 to hold the shoulder end 28 of the plate 27 in engagement with the plate 33 on the lever 16. The engagement may be made more certain by the formation of a notch in the arm 26 at the shoul-

der end 28 of the plate 27. As the bobbins of the spinning frame fill, the traverse rod is moved toward the end 8 of the frame and the rod 37 participates in this movement. When the bobbins have become filled to a predetermined extent the end 38 of the rod 37 makes contact with the edge 39 of the arm 29 and causes a movement of the lever 25 to carry the shoulder 28 out of the path of the end 33 of the lever 16 until ultimately the lever escapes from the latch notch and shoulder and the spring 24 becomes active to rock the lever 16 in a direction to shift the rod 6 and belt shifter 2, so as to carry the belt 3 from the tight pulley 4 on to the loose pulley 5, whereupon the spinning frame stops. This prevents the bobbins from overrunning and effects a saving both in time and material.

The application of the device to existing spinning machines requires no modification at all of such machines other than the possible boring of a hole through the cross piece 12 of one of the end frames, all the rest of the parts being attachable to the frame without any change whatever in the structure thereto.

When it is desired to again start the machine, the shifter rod 6 is manipulated in the usual manner and the stop motion structure is thus automatically reset.

The traverse rod is a part of machines as already installed, and its motion is utilized for the operation of the stop motion.

The present invention does not interfere in any manner with the spinning frame, but adds greatly to its efficiency by automatically stopping the machine when the bobbins are full.

What is claimed is:

1. A stop motion attachment for a spinning frame provided with a shifter and a traverse rod, comprising a rockable latch lever, a support therefor constructed for attachment to the frame of the machine, means constructed for attachment to the shifter rod and to engage the rockable latch lever, a latch member separate from and in operative relation to the latch lever to lock the latter in one position, means constructed for attachment to the traverse rod and shaped to engage the latch member to operate it on a predetermined movement of the traverse rod, and a spring carried by the supporting means for the latch lever for moving the latter in a direction to actuate the shifter to stop the machine.

2. In a spinning frame provided with a shifter rod and a traverse rod, a bracket having spaced arms and adapted to be attached to the frame of the machine, a lever mounted on one of the arms of the bracket, another lever mounted on the other arm of the bracket, and said levers having coacting latch parts, a spring carried by the bracket

in position to move the first-named lever in one direction, the second-named lever being normally constrained to move in a direction to engage and hold the first-named lever, a member adapted to be attached to the shifter rod and having a portion shaped to engage the corresponding end of the first-named lever, and a member having means for attachment to the traverse rod and shaped to engage the second-named lever to move it in opposition to its normal tendency.

3. A stop motion attachment for spinning frames comprising a bracket adapted to be attached to the spinning frame, two rock levers mounted on the frame with coacting ends shaped to cause a latching together of the levers, one of the levers having a normal tendency to move toward the other and the other lever being provided with a spring tending to move it in a direction away from its latched position, and means adapted to be attached to moving parts of the spinning frame for actuating the respective levers.

4. In a spinning frame provided with a shifter rod and a traverse rod, a latch lever carried by a fixed portion of the spinning frame, a spring tending to move the latch lever in one direction, a connection between the latch lever and the shifter rod of the spinning frame, another lever having a normal tendency toward the latch lever and shaped to engage and hold the latch lever against the tendency of the spring, and means adapted to be attached to the traverse rod and movable thereby into engagement

with the second-named lever to cause its disengagement from the latch lever.

5. In a spinning frame provided with a shifter rod and a traverse rod, a bracket adapted to be attached to a fixed portion of the spinning frame, a bolt for connecting the bracket to the fixed portion of the spinning frame and provided with an extension, a lever mounted on the bracket with one arm traversed by the extension of the bolt, a spring surrounding the bolt extension and engaging the corresponding arm of the lever, a rod adapted to be attached to the shifter rod of the spinning frame and shaped to engage the other arm of the lever, an angle lever mounted on the bracket and having one arm in the path of the first-named arm of the first-named lever and shaped to engage and latch the first-named arm of the first-named lever when the shifter rod is in one position, said second-named lever having a normal tendency toward the first-named lever, and a rod having means for attachment to the traverse rod and shaped to engage the second-named lever to move it against its normal tendency to cause the release of the first-named lever from its latched position.

In testimony, that we claim the foregoing as our own, we have hereto affixed our signatures in the presence of two witnesses.
